UNITED STATES PATENT OFFICE.

SANFORD S. VAUGHAN, OF OAK PARK, ILLINOIS.

CARPENTER'S HAND-HAMMER.

1,356,673.

Specification of Letters Patent. Patented Oct. 26, 1920.

Application filed November 24, 1917. Serial No. 203,656.

To all whom it may concern:

Be it known that I, SANFORD S. VAUGHAN, a citizen of the United States, and a resident of Oak Park, in the county of Cook and 5 State of Illinois, have invented certain new and useful Improvements in Carpenters' Hand-Hammers, of which the following is a specification.

My invention relates to hand hammers 10 such as are used by carpenters for driving nails. It has special reference to an addition to the hammer handle, resulting in a combined hammer and nail waxing device, the object of which is to afford convenience 15 to the workman and effect a saving in his time, labor and material.

When carpenters are driving nails in hard wood, for instance in laying hard wood floors, it is their practice to coat at least 20 the point portions of the nails with beeswax to facilitate their passage through the wood. The workman usually carries a chunk of the wax in his overalls pocket or keeps the same lying handy while being thus engaged. Frequently 25 the wax so handled becomes lost or misplaced, usually it is full of dirt and chips, and at all times it is subject to considerable wastage in the breaking away of pieces while being used and also by being 30 rubbed and worn by the tools and other objects in the pockets and in the kit.

The present improvements contemplate a supply of the wax in a substantially enclosed well or recess in the handle of the 35 hammer used, the receptacle being adapted to contain a material quantity of the wax and maintain it in clean condition, avoid its wastage, insure its presence when and where needed, and render the operation of coating 40 the nail rapid and easy.

In the accompanying drawings, forming a part hereof, Figure 1 is a side view of a hammer showing the well and its closure by dotted lines;

45 Fig. 2 is a sectional fragment showing the closure for the well in its initial form and location ready to be secured in substantially permanent position; and

50 Fig. 3 is a similar section showing the device of Fig. 2 with the closure in its final relative position.

Preferably axially of the handle a boring is made of substantial diameter resulting in the well 10, having a sufficient depth to receive 55 a considerable portion of the larger sized nails. In practice I make the well

about one and one-half inches deep. Surrounding the open end of the well 10 the wood is preferably countersunk or recessed, as shown at 11, to a depth sufficient to accommodate the preferably metallic plate-like closure 13 whereby the plate will lie preferably almost flush with the handle end. The plate is provided with a simple opening 15 therethrough which is relatively small with 60 respect to the diameter of the well and is preferably only large enough to admit easily the larger sizes of nails which are likely to be used. A three-sixteenths of an inch opening 65 will be sufficient for all ordinary purposes. 70

The plate 13 is preferably a circular disk-like metallic stamping initially concavo-convex in form, and, when in its initial shape, as shown in Fig. 2, has a diameter just sufficient to enable it to enter the circular recess 11, which circular recess is preferably slightly deeper than the thickness of the metal 13. By means of pressure, such as a hammer blow, the disk 13 is flattened into its shape seen in Fig. 3, whereupon, owing 80 to its enlargement in diameter due to flattening, it becomes tightly engaged with the surrounding wood by compressing the fibers thereof and causing an overlapping bur seen at 20, Fig. 3, the disk 13 being thus 85 quite rigidly held in position. As the handle becomes older and more seasoned the contraction of the wood tends to bind the disk 13 still more tightly. While the disk 13 may be sprung out of the recess 11 through 90 the employment of considerable force I contemplate the filling of the well 10 through the opening 15, which may conveniently be done by melting the wax and pouring it through the opening 15 or by forcing the 95 wax directly through the hole.

In operation the workman holds the hammer in one hand while reaching for a nail with the other. Having picked up a nail he simply inserts the end thereof through the 100 nail hole 15 and into the body of the wax 18 causing it to become coated thereby. It sometimes happens that a considerable quantity of the wax adheres to the nail, but, owing to the small size of the opening in the 105 closure plate, the excess is automatically scraped away and remains in the well, and thus a saving of wax is effected in this regard. The restricted size of the opening 15 and its preferred axial arrangement with respect to the well effectively avoids the loss 110 of particles of wax which may become loos-

ened from the main body, and the opening is also so located with respect to the sides of the handle that when the handle is lying about dirt, chips, shavings and the like are 5 effectively prevented from getting into the well.

An important feature of these improvements is in the fact that the end of the handle is preserved for use by the workman as 10 a mallet or setting tool in the many instances of practice wherein it is not desired to contact the work with the metallic head. Other important advantages are had in the simplicity of construction, the relatively large 15 amount of lubricant which may be carried, the lightness of the added part, and the ease of operation in service.

It is not broadly new to provide a hammer handle with a well therein for a lubricant 20 together with a closure for the well, and I do not claim such as my invention. Reference should be had to the appended claims to determine the scope of the invention herein set forth.

25 I claim:

1. A wooden hammer handle having a

longitudinal bore in one end forming a well and having a countersink about the opening of the well, a plate-like member having lateral dimensions greater than the corresponding dimensions of the said countersink, said member being within the countersink and compressing the wood fibers at the edges thereof so that said fibers overhang the peripheral edges of the said member, the member having a hole therethrough leading into the well. 30

2. A wooden hammer handle having a longitudinal boring in one end forming a well for wax or similar lubricant and having a countersink about the opening of the well for accommodating therein a plate-like closure, a flat plate-like closure locked against movement in said countersink by wood fibers overhanging the outer peripheral edge of the closure, the wood fibers at the edge of and in the plane of the closure being under compression, the closure having a hole therethrough of less cross area than that of the well and leading into the well, 40 45 substantially as set forth and described.

SANFORD S. VAUGHAN.
